TILTING TRAP.

Application filed August 4, 1922. Serial No. 579,656.

The invention relates to tilting traps.

The objects of the invention are to provide improved means for tiltably supporting the drum; improved means for operating the 5 valve connections for controlling the flow of fluid to the drum; means for balancing the end pressure upon the trunnion pipe to prevent frictional retardation; and to provide a structure in which the trunnion pipe 10 extends to one side of the drum only; and to provide a tilting trap which is simple in construction and reliable and efficient in operation.

The invention consists in the several novel 15 features hereinafter set forth and more particularly defined by claims at the conclusion hereof.

In the drawings: Fig. 1 is a longitudinal section through the trunnion-pipe, of a trap 20 embodying the invention. Fig. 2 is a section taken on line 2—2 of Fig. 1. Fig. 3 is a section on line 3—3 of Fig. 1.

The invention is exemplified in a trap which comprises a drum or tank 4 which is 25 adapted to receive the condensate, may be of any suitable construction and is adapted to tilt in one direction and discharge the fluid when a predetermined quantity has been delivered into it and to tilt back to 30 its normal position, when the fluid has been discharged, as well understood in the art. The trap is supported upon a suitable base 5. The trunnion-pipe supports the drum or tank, has a passage therein for the 35 outflow of the fluid or condensate and comprises a hollow vertical member 6 provided with a top flange 7, on which the drum 4 is rigidly secured, and a tubular laterally extending member 8 which is fixedly 40 secured to member 6 by a screw-thread connection 9. A circular bearing surface 10 is formed on member 8 at one side of the vertical member 6 and a similar surface 11 is formed on the closed other side of member 6. 45 A series of rollers 13, each confined in an arcuate groove 12, engage the circular bearing-surfaces 10 and 11 respectively, to support the drum at both sides of the supporting member 6. Grooves 12 are formed in a 50 bracket 15 which is fixedly mounted upon base 5. These bearings are open at the top as illustrated in Fig. 2, to minimize the frictional resistance to the tilting of the drum,

there being no upward displacing stresses. 55 One feature of the invention consists in dispensing with the trunnion pipe at one side and using the other side for the delivery and discharge of the fluid and therefore member 6 is closed at the side at which the bearing surface 11 is formed. 60

A fitting 16, which is provided with a base-flange 17, is rigidly secured to the base 5. This fitting is disposed adjacent one end of the trunnion-pipe and is adapted to receive the fluid to be delivered to the drum 65 and to receive the fluid therefrom. A pipe 18 is connected to a chamber 19 formed in the outer end of fitting 16 and delivers the fluid or condensate to said chamber. A pipe 20, to deliver the fluid to the drum, is fixedly 70 secured in the inner wall of chamber 19, extends inwardly through member 8 of the trunnion-pipe and into member 6 and is connected by an elbow 22 to a riser pipe 23, which discharges the condensate into the upper portion of the drum 4. This exemplifies 75 a structure in which fluid is delivered into the upper portion of the tiltable drum by a stationary pipe connected to the fitting to which the inlet pipe is connected and extending through the trunnion-pipe.

A section of tubing 24 fits into the outer end of member 8 of the trunnion-pipe and is secured to rotate therewith by interfitting connections consisting of tongues 25 fitting 85 into correspondingly shaped recesses in the inner periphery of said member. This tube rotates when the drum and trunnion-pipe are tilted and extends outwardly into a chamber 26 in fitting 16. An arm 27 is secured 90 to the outer end of tube 24 and operates a valve 28, which controls the outflow of the fluid from the drum. Valve 28 closes against a seat 29 which opens into a discharge chamber 30, to which the discharge pipe 31^a is 95 connected. Valve 28 is secured to a stem 31 which is slidably guided in a plug 32 which is screw-threaded to the top of fitting 16. Arm 27 is split, as at 33, and a screw 34 is 100 adapted to adjustably clamp the arm in the desired position on tube 24. When the drum is tilted into one of its positions, arm 27 will bear upon and close valve 28 and when the drum is tilted into its other position, the arm will engage a shoulder 35 on stem 31 to lift 105 and open the valve.

To prevent the escape of fluid from fitting 16 and around tube 24, a fluid-tight connection is provided. This comprises a ring 37, which is fixed in the end of member 8 of the trunnion-pipe, and has a fluid-tight surface to engage a ring 38 which is connected to a housing 39 on fitting 16, by a metallic diaphragm 40. The outer margin of this diaphragm 40 is secured to said fitting by an inwardly flanged ring 41 which is screw-threaded to housing 39 and its inner margin is secured to ring 38 by a collar 42 which fits around tube 24 and is connected by a screw-thread 43 to ring 38, so that the inner margin of the diaphragm will be clamped between said ring and said collar. A spring 44 in housing 39 is interposed between fitting 16 and collar 42 to press the ring 38 into contact with ring 37. The latter is preferably formed of self-lubricating metal to minimize frictional resistance to the tilting of the trunnion pipe, whilst maintaining a fluid-tight connection with ring 38. The inner face of the diaphragm is exposed to pressure in chamber 26 in fitting 16 and the trunnion-pipe, there being sufficient clearance between tube 24 and the fitting for this purpose. As a result, the pressure in the fitting and trunnion pipe will exert pressure upon the diaphragm 40 to hold ring 38 in contact with ring 37, whilst permitting longitudinal movement of both rings, due to expansion and contraction, resulting from temperature-changes.

In a structure in which the trunnion-pipe extends to one side only, and is connected to a stationary fitting, there is a preponderance of endwise fluid-pressure away from the fitting which tends to shift the trunnion-pipe longitudinally on its rollers 13. To substantially offset or equalize this endwise pressure, a diaphragm 45, which is subjected to the pressure of fluid in a counter-direction, is provided. This diaphragm is secured by a nut 49' to a head 46 which engages a stop 47 on the trunnion pipe. This stop has one of its ends fitting into a corresponding recess in head 46 and is adjustably secured to the closed side of the trunnion-pipe by a screw 48. A nut 49' on a screw 50 secures head 46 to the diaphragm 45. Said screw is provided with a stem 51 which is slidable in a guide-socket 52. The outer margin of diaphragm 45 is clamped by a collar 53 to a fitting 54 which is rigidly secured to the base 5 and is provided with a fluid-chamber 55 at the inner side of the diaphragm. A pipe 56 has one of its ends connected to the inlet chamber 19 in the fitting 16 and its other end to the chamber 55 in the fitting 54 to conduct some of the fluid under pressure to diaphragm 45. As a result, the diaphragm 45 will be subjected to the fluid under pressure from chamber 19 to exert pressure in a counter direction, to

substantially offset or balance the preponderating pressure against the trunnion-pipe in the other direction. By balancing the pressure in this manner, the tilting drum will be sensitively supported, so that it will accurately respond to the weight of the column of condensate therein.

In operation, the fluid to be trapped, such as condensate under pressure, will enter chamber 19 in fitting 16 through pipe 18 and will pass through the stationary pipe 20 and the riser pipe 23 to the upper portion of the drum. When a sufficient quantity of condensate has accumulated in the drum to require its discharge, the drum will be tilted in one direction, the trunnion-pipe will rotate with the drum and cause arm 27 to engage abutment 35 and open valve 28. Thereupon, the condensate will be discharged through the trunnion pipe, tube 24 and chamber 26 into the chamber 30. When the drum has been emptied, it will tilt reversely and cause the arm 27 to close valve 28.

The invention exemplifies a tilting trap in which the trunnion pipe rotates around a stationary inlet pipe; in which the trunnion pipe extends to one side only; in which anti-friction bearings sustain the drum and the end pressure on the trunnion pipe is substantially balanced to minimize friction; in which an arm or valve operating device is enclosed in the fitting to which the trunnion pipe is connected; in which a fluid-tight connection is made between the trunnion-pipe and the fitting without the use of packing; and which is sensitive and efficient in its operation.

The invention is not to be understood as restricted to the details set forth, since these may be modified within the scope of the appended claims, without departing from the spirit and scope of the invention.

Having thus described the invention, what we claim as new and desire to secure by Letters Patent is:

1. In a tilting trap, the combination of a tiltable drum, a trunnion pipe secured to and movable with the drum having a fluid passage connected to the drum, means to rotatably support the trunnion-pipe, said trunnion-pipe comprising upwardly and laterally extending members, a stationary pipe in the trunnion pipe comprising members extending through the laterally and upwardly extending members of the trunnion-pipe, a stationary fitting in which the stationary pipe is secured, and a valve in said fitting operated by the trunnion pipe.

2. In a tilting trap, the combination of a tiltable drum, a trunnion pipe secured to and movable with the drum having a fluid passage connected to the drum, means to rotatably support the trunnion-pipe, said trunnion-pipe comprising upwardly and laterally extending members, a stationary pipe in the

trunnion pipe comprising members extending through the laterally and upwardly extending members of the trunnion-pipe, a stationary fitting in which the stationary pipe is secured, a valve in said fitting operated by the trunnion-pipe, and a fluid-tight connection between the fitting and the laterally extending member of the trunnion-pipe.

3. In a tilting trap, the combination of a tiltable drum, a trunnion pipe secured to and movable with the drum, having a fluid passage connected to the drum, a stationary pipe in the trunnion pipe communicating with the drum, a stationary fitting in which the stationary pipe is secured, and a valve inside of the fitting and operated by the trunnion-pipe.

4. In a tilting trap, the combination of a tiltable drum, a trunnion pipe secured to and movable with the drum, having a fluid-passage connected to the drum, a stationary pipe in the trunnion pipe communicating with the drum, a stationary fitting in which the stationary pipe is secured, a valve inside of said fitting, an arm on said trunnion-pipe for shifting said valve, and a fluid-tight connection between the trunnion-pipe and said fitting.

5. In a tilting trap, the combination of a tiltable drum, a trunnion-pipe having a fluid-passage therethrough and comprising an upwardly extending portion fixedly connected to the bottom of the drum and a portion extending to but one side thereof, bearings for rotatably supporting the trunnion-pipe, a valve adjacent the outer end of the trunnion-pipe, a stationary pipe extending through said trunnion-pipe, a stationary fitting for said valve, and valve-operating means in said fitting and between the end of the trunnion-pipe and said valve.

6. In a tilting trap, the combination of a tiltable drum, a trunnion pipe having a fluid-passage therethrough and comprising an upwardly extending portion fixedly connected to the bottom of the drum and a portion extending to but one side thereof, bearings for rotatably supporting the trunnion-pipe, a valve adjacent the outer end of the trunnion-pipe, a stationary pipe extending through said trunnion-pipe, a stationary fitting for said valve, a fluid-tight connection between the trunnion-pipe and the fitting, and valve-operating means in said fitting and between the end of the trunnion-pipe and said valve.

7. In a tilting trap, the combination of a tiltable drum, a trunnion pipe rigid and having a fluid passage communicating with the drum, means for rotatably supporting the trunnion pipe, a connection for delivering fluid under pressure to the drum from one side thereof, a valve controlled by the tilting of the drum for controlling the fluid, and

fluid operated means to exert endwise counter-force on the trunnion-pipe to substantially balance the unilateral pressure of the fluid.

8. In a tilting trap, the combination of a tiltable drum, a trunnion pipe rigid and having a fluid passage communicating with the drum and extending to one side only, means for rotatably supporting the trunnion pipe, a connection for delivering fluid under pressure to the drum from the same side thereof, a valve controlled by the tilting of the drum for controlling the fluid, and fluid operated means to exert endwise counter-force on the trunnion-pipe to substantially balance the unilateral pressure of the fluid.

9. In a tilting trap, the combination of a tiltable drum, a trunnion pipe rigid and having a fluid passage communicating with the drum, means for rotatably supporting the trunnion pipe, a stationary pipe for delivering fluid under pressure to the drum extending through said trunnion pipe, a valve controlled by the tilting of the drum for controlling the fluid, and fluid operated means to exert endwise counter-force on the trunnion-pipe to substantially balance the unilateral pressure of the fluid.

10. In a tilting trap, the combination of a tiltable drum, a trunnion pipe rigid and having a fluid passage communicating with the drum, means for rotatably supporting the trunnion pipe, a stationary fitting at one end of the trunnion-pipe, a fluid-tight connection between the fitting and the trunnion-pipe, a pipe for delivering fluid under pressure from the fitting to the drum, a valve controlled by the tilting of the drum for controlling the fluid, and fluid operated means to exert endwise counter-force to substantially balance the unilateral pressure of the fluid on the trunnion-pipe.

11. In a tilting trap, the combination of a tiltable drum, a trunnion pipe rigid and having a fluid passage communicating with the drum, means for rotatably supporting the trunnion pipe, a stationary fitting at one end of the trunnion-pipe, a fluid-tight connection between the fitting and the trunnion-pipe, a pipe for delivering fluid under pressure from the fitting to the drum, a valve controlled by the tilting of the drum for controlling the fluid, and means to exert a counter-pressure to substantially balance the unilateral pressure of the fluid on the trunnion-pipe comprising a diaphragm and a fluid connection between the diaphragm and the fitting.

Signed at Chicago, Illinois, this 22nd day of July, 1922.
